UNITED STATES PATENT OFFICE.

WASYL ZADOROZNY, OF MEACHAM, SASKATCHEWAN, CANADA, ASSIGNOR OF ONE-HALF
TO TONY ZYGIEL, OF HAMILTON, ONTARIO, CANADA.

COMBINED BAYONET AND WIRE-CUTTER.

1,316,664.

Specification of Letters Patent.

Patented Sept. 23, 1919.

Application filed April 16, 1919. Serial No. 290,579.

To all whom it may concern:

Be it known that I, WASYL ZADOROZNY, a citizen of Austria, residing at Meacham, Province of Saskatchewan and Dominion of Canada, have invented certain new and useful Improvements in Combined Bayonets and Wire-Cutters, of which the following is a specification.

This invention has as its principal object 10 the provision of a simple device attached to the hilt of the bayonet and operable in an easy manner, whereby wires or the like may be readily severed so as to obtain a passage through wire fences, entanglements and the 15 like obstructions.

These and other like objects are attained by the novel construction and combination of parts hereinafter described and shown in the accompanying drawings, forming a material part of this disclosure, and in which—

Fig. 1 is a side elevational view showing a conventional type of gun, and indicating the application of the invention.

Fig. 2 is a fragmentary perspective view 25 showing the operating parts of the wire cutter as combined with the bayonet, and

Fig. 3 is an enlarged longitudinal sectional view showing the actuating mechanism by which the wire cutting jaws are operated.

Referring to the drawings, a conventional type of gun is shown in Fig. 1, the same comprising a butt 10, lock 11, and stock 12, in which is attached the barrel 13, the same extending outwardly to the front as is common.

Engaged with the outwardly extending end of the gun barrel 13, by ordinary devices, is a bayonet 14, having a double cutting edge, and a sharp dagger-like point 15, the opposite end being contained within a handle 16, adapted to be manually operated and held to the gun stock by ordinary fastenings passing through an opening 17, formed 40 in the enlarged hilt 18, while at the juncture of the hilt and blade is an eye or loop 19 containing an opening 20 adapted to slip over the extending end of the gun barrel 13, the arrangements being such as to in no wise 45 impede the free and ordinary use of the gun, or obstruct the sights thereof.

Formed with the eye 19, is an encircling element 22, extending to some distance downward, and pivoted upon its lower portion,

by the screw 23, is a bell-crank lever jaw 24, 55 coincident with an extending element 25, integral with the element 22, and containing an opening 26, a similar opening 27 being provided in the extending jaw 24, of the bell-crank so that as they are moved relatively, they sever any article entered therebetween.

The opposite, vertical arm 28 of the bell-crank lever has secured to it, by the pin 29, a connecting link 30, extending substantially 65 parallel with the bayonet handle 16 rearwardly to a point where it is engaged with the front end of a wire link 32, supported in bands 33, encircling the stock of the gun and ultimately entering a rod 34, extending 70 outwardly from the front of a casing 35, secured to the stock of the gun below and slightly forward of the lock 11.

This casing 35, contains a cylindrical opening 36, in which is a plunger 37, having a 75 helical cam slot 38, engageable in which is a pin 39, set in the casing, so as to cause the plunger 37 to rotate when moved longitudinally therein, the plunger being rigidly secured to the rod 34, and pressed forward by 80 a coiled compression spring 40, abutting against one end of the casing 36 at one end, and against the rear end of the plunger 37 at the other.

The rearward end 41 of the rod 34 is bent 85 outwardly to form a handle 42, furnished with an operating knob 43 by which it may be rotated, and obviously when the rod 34 is rotated, the plunger 37 is moved longitudinally, due to the pin 39 engaging within the 90 cam slot. The outer end of the rod 34, contains a cylindrical opening 44, in which, at the bottom is a head 45, formed with the wire 32, the head being free to rotate therein, and held by a bushing 46, secured by a screw 47, 95 so that when the handle 42 is rotated, the rod 34 is similarly rotated and moved rearwardly together with the connecting wire link 32, but owing to its rotatable connection with the rod 34, the link is merely drawn rearwardly and not rotated, and obviously, through its connections with the bar 30 of the bell-crank connection, and by the bell-crank lever elements the cutting edges 27 are operated with respect to the fixed cutting edges 26, severing a wire or whatever other article may have been entered therebetween.

Having thus described my invention and set forth the manner of its application and use, what I claim as new and desire to secure by Letters Patent, is—

- 5 1. In a device of the class described, the combination with a gun having a lock, stock and barrel, of a bayonet secured to the barrel and front end of said stock, a fixed wire cutting jaw rigidly engaged with said bayonet near the hilt thereof, a bell-crank lever pivoted adjacent to said fixed blade, a movable jaw formed with said bell-crank lever, a pivoted connection extended rearward from the longer arm of said bell-crank lever substantially parallel with the stock of said gun, a casing secured to said gun below the lock thereof, a cam movable in said casing, means for actuating said cam, and connections between said cam and said bell-crank lever, whereby said movable jaw is actuated with reference to said fixed jaw.
- 10 2. In a device of the class described, the

combination with a gun having a lock, stock and barrel, and a bayonet rigidly secured to said barrel and front end of said stock, of 25 a fixed wire cutting jaw secured to said bayonet, a bell-crank lever pivoted on said fixed jaw, a movable jaw formed with said bell-crank lever, pivoted connections extended rearwardly from the longer arm of said 30 bell-crank lever, a casing secured to said stock below said lock, a plunger movable in said casing, means for normally moving said plunger forward, a cam recess formed in said plunger, a pin in said casing engaging said 35 cam recess whereby said connections are moved rearwardly when said cam plunger is rotated, and means for rotating said plunger, said rotating means extending rearwardly below the lock of said gun. 40

In testimony whereof I have affixed my signature.

WASYL ZADOROZNY.
